DESIGN FOR A BURNER KNOB FOR GAS
STOVES

Richard I. Felver, Pittsburgh, Pa., assignor to
Standard Gas Equipment Corporation, Balti-
more, Md., a corporation of Maryland

Application October 22, 1946, Serial No. 134,177

Term of patent 14 years

(Cl. D81—25)

To all whom it may concern:

Be it known that I, Richard I. Felver, a citizen of the United States, residing at Pittsburgh, county of Allegheny, State of Pennsylvania, have invented a new, original, and ornamental Design for a Burner Knob for Gas Stoves, of which the following is a specification, reference being had to the accompanying drawing, forming part there-
of.

Figure 1 is a face view of a burner knob for gas stoves showing my new design.

Figure 2 is an edge view, partly in cross section to show the face contour of the knob.

Figure 3 is a face view with the knob rotated to an "on" position.

I claim:

The ornamental design for a burner knob for gas stoves, as shown.

RICHARD I. FELVER.
